[57] CLAIM

The ornamental design of an apparel in a bottle, as shown and described.

DESCRIPTION

FIG. 1 is a perspective view showing my new apparel in a bottle;

FIG. 2 is a front view thereof; the rear and side views being similar except for the threading on the neck portion and the pattern of the apparel, the undisclosed threading on the neck portion and the pattern of the apparel form no part of the claimed design;

FIG. 3 is a top view thereof; and,

FIG. 4 is a bottom view thereof.
